UNITED STATES PATENT OFFICE

95,071

DESIGN FOR A MULTIPLE-UNIT INSULATOR SUPPORT FOR BUS BARS

Harold H. Rudd, Greensburg, Pa., assignor to
Railway & Industrial Engineering Co., Greens-
burg, Pa., a corporation of Pennsylvania

Application December 4, 1934, Serial No. 54,264

Term of patent 7 years

To all whom it may concern:

Be it known that I, Harold H. Rudd, a citizen of the United States, residing at Greensburg, in the county of Westmoreland and State of Pennsylvania, have invented a new, original, and ornamental Design for Multiple-Unit Insulator Support for Bus Bars, of which the following is a specification, reference being had to the accompanying drawing, forming part thereof, and wherein:

Fig. 1 is a perspective view of the multiple-unit insulator support for bus bars;

Fig. 2 is a side elevation; and

Fig. 3 is a top plan view of the same.

I claim:

The ornamental design for a multiple-unit insulator support for bus bars, as shown.

HAROLD H. RUDD.
